UNITED STATES PATENT OFFICE.

WILLARD E. DOW, OF BRAINTREE, MASSACHUSETTS.

REMOVABLE ANVIL-CONTACT AND BRIDGE-SUPPORT FOR ELECTRIC VIBRATORS.

No. 821,028.

Specification of Letters Patent.

Patented May 22, 1906.

Application filed March 13, 1905. Serial No. 249,822.

To all whom it may concern:

Be it known that I, WILLARD E. Dow, a citizen of the United States, residing at Braintree, in the county of Norfolk and State 5 of Massachusetts, have invented an Improvement in a Removable Anvil-Contact and Bridge-Support for Electric Vibrators, of which the following description, in connection with the accompanying drawings, is a 10 specification, like numerals on the drawings representing like parts.

My invention relates to electric vibrators for operating induction-coils, and has for its object the provision of means for removing 15 the adjustable contact or "anvil," so called, for inspection or cleaning without changing its adjustment in any way. To this end I provide the contact member (a usual screw-contact being commonly employed) with a 20 holder which co-operates with the supporting-bridge to removably lock said contact rigidly in place and yet permit the instant removal of said contact and holder without disturbing their relative adjustment. In other words, 25 the adjustment of the contact takes place with reference to the holder, and the holder and bridge have interlocking means or other devices or formation for permitting the holder to be instantly put in place or removed therefrom without disturbing said adjustment. In 30 the preferred embodiment of my invention said holder and contact are maintained in locked position relatively to the bridge by yielding means.

35 My invention is especially adapted to automobiles.

In the accompanying drawings, in which I have shown two embodiments of my invention, Figure 1 represents conventionally in 40 side elevation an induction-coil and its vibrating hammer provided with one form of my removable bridge-piece and contact, a portion of the bridge-piece being broken away for showing the internal relative arrangement 45 of parts. Fig. 2 is a top plan view of the contact-holder. Fig. 3 is a central longitudinal sectional view of the engaging end of the bridge-piece. Fig. 4 is an isometric view of the bridge-piece looking downwardly at the 50 rear end thereof; and Figs. 5, 6, and 7 are enlarged views of a different or modified construction, Fig. 5 showing the holder, contact, and bridge-piece in side elevation, Fig. 6 showing the holder in bottom plan, and Fig. 55 7 showing a top plan of the forward end of the bridge.

For convenience of illustration I have merely indicated conventionally a coil 1, provided with a vibrating hammer or contact-breaker 2 for operating between the core end 60 3 of the coil and an opposite contact 4.

The contact 4 is shown as a threaded post or screw 5, operated by a thumb-nut 6 in usual manner. This screw 5 has threaded engagement at 7 (see Fig. 2) with a block-like 65 split holder 8, which may have a clamping-screw 9 for binding the screw 5 in any given adjustment in said holder. Coöperating with this holder 8 is a bridge-piece 10, (which, it will be understood, will be secured to an insulating-slab or any convenient portion of the coil in the same manner as the ordinary bridge,) having two upwardly and forwardly projecting arms 11 12, at whose extreme forward lower corners are inwardly-projecting 70 ledges 13 and rearwardly therefrom a cross-bar or retaining-stud 14. Beneath said stud 14 is a leaf-spring 15, shown as secured by a nut 16 to project forwardly and upwardly just beneath the stud 14. The rear end of 80 the holder is peculiarly shaped, as is clearly shown in Fig. 1, having an angular notch or slot 17 tending obliquely downward a short distance and thence obliquely rearwardly, so as to form a retaining-pocket for the stud 14. 85 The extreme rear end 18 of the holder is approximately flat and at right angles to the general direction of the holder and terminates in a depending portion 19 for wedging against the free end of the spring 15, so as to retain 90 the holder not only in immovable engagement with the stud 14, but also in contact with the supporting-ledges 13.

From the foregoing description it will readily be understood that whenever the user of 95 the vibrator desires to inspect the platinum point of the contact 4 or desires to clean the same or whenever he wishes to kill the vibrator temporarily by placing the contact 4 in his pocket (while leaving the automobile, 100 for instance) he simply disengages the holder-notch 17 from the retaining-stud 14 without disturbing the adjustment of the screw-contact in its threaded aperture 7 in any way. In order to release the holder and its contact 105 from the locked position shown in Fig. 1, the user simply moves the holder 8 over to the left in the direction of the arrow, Fig. 1, until the shouldered inner end of the notch 17 can readily slide over the stud 14, whereupon the 110 notched end of the holder is moved forward sufficiently to disengage the notch from said

stud. After having cleaned or inspected the contact-point the operator simply hooks the notch 17 back onto the stud 14 and shoves the free end of the holder down against the 5 ledges 13, where it is tightly held by the spring 15.

I am aware that it is not new to provide means for permitting the contact to be moved into position for cleaning and inspection, this 10 being old in various patents—as, for instance, in Hard, No. 371,755, and in Palm-leaf, No. 550,688—and I do not, therefore, claim the same; but I believe it is new to provide a removable contact-holder arranged to 15 interlock with the bridge-piece for permitting the instant removal of the contact without interfering with its adjustment means, and I believe that my invention is new in various other features which will be pointed out in 20 the claims.

In Figs. 5 to 7 I have shown a further embodiment of my invention, the bridge 10 having its free end extending forwardly in the same shape as before and being longitudinally slotted to constitute two receiving-arms 20 21, having an opening 22 for receiving a tubular holder 23, threaded on its inner side 24 to receive the screw 5 of the contact 4 and provided on its outside with projecting studs 25 or pins 25, constituting a cross-bar for entering the slot 26 of the bridge-piece. Having inserted the holder 23 in the opening 22 of the bridge-piece sufficiently to permit the studs or pins 25 to pass beneath the latter, the 30 holder is turned at right angles, so as to bring said studs into notches 27 in the under side of the bridge-piece, where they are held tightly by a coiled spring 28, which surrounds the tubular holder 23. The holder 23 is split at its 35 upper end, as indicated at 29, and provided with a clamping-screw 30 for clamping the screw 5 in immovable adjustment, acting the same as the screw 9 in the previously-described embodiment of my invention.

45 When the contact or contact-point 4 and its removable support or split holder 8 or 23 are removed from their bearing or disengagement with the bridge-piece, they thereby permanently disrupt the primary circuit of the 50 induction-coil, and when replaced in their bearing they reestablish said primary circuit to the extent that the induction-coil is then in working condition for automatically disrupting and reestablishing the circuit upon 55 the closing of said circuit by the usual interrupter or other circuit-closing device. (Not shown.)

As already intimated, I do not intend to 60 restrict myself to the constructional details herein shown, as my invention is capable of various other embodiments and modifications without departing from the spirit and

scope thereof as set forth in the following claims, taken in connection with this description.

65

Having described my invention, what I claim as new, and desire to secure by Letters Patent of the United States, is—

1. In an induction-coil vibrator, an adjustable contact-point adapted to be removed 70 from its bearing, and replaced, without altering the adjustment.

2. In an induction-coil vibrator having an adjustable contact-point, means supporting said contact-point in a manner permitting its 75 removal and replacement without disturbing the adjustment.

3. In a vibrator for induction-coils having an adjustable contact-point, means for disrupting and reestablishing the primary circuit, consisting of a removable support for 80 said adjustable contact-point.

4. In an electric vibrator, a vibrating contact-breaker, a holder, a contact adjustable therein and intermittently engaged by said 85 contact-breaker, and means permitting said holder and contact to be instantly removed or placed in position without disturbing the adjustment of said contact.

5. An electric vibrator, having a removable contact-holder, a contact adjustable therein, a vibrating contact-breaker intermittently closing and breaking the circuit through said contact, and yielding means for normally maintaining said holder and its 95 contact in operative position.

6. An electric vibrator, provided with a bridge having a bifurcated free end, and a contact and its holder normally retained by said bifurcated free end, said holder and 100 bridge having coöperating locking means for permitting the instant removal of said holder and contact.

7. An electric vibrator, provided with a bridge having a bifurcated free end, and a 105 contact and its holder normally retained by said bifurcated free end, said holder and bridge having a coöperating notch and stud for removably locking them together.

8. An electric vibrator, provided with a 110 bridge having a bifurcated free end, and a contact and its holder normally retained by said bifurcated free end, said holder and bridge having a coöperating notch and stud for removably locking them together, and a 115 spring for yieldingly holding said notch and stud in locking position.

In testimony whereof I have signed my name to this specification in the presence of two subscribing witnesses.

WILLARD E. DOW.
